Patented Mar. 7, 1916.

UNITED STATES PATENT OFFICE.

JOHN P. MURCZKO, OF BRIDGEPORT, CONNECTICUT.

TABLE.

1,174,889.

Specification of Letters Patent. Patented Mar. 7, 1916.

Application filed February 10, 1915. Serial No. 7,819.

To all whom it may concern:

Be it known that I, JOHN P. MURCZKO, a subject of Hungary, residing at Bridgeport, in the county of Fairfield and State of Connecticut, have invented new and useful Improvements in Tables, of which the following is a specification.

The present invention has for its object the provision of a table of novel construction, primarily intended for use on board ship, whereby the top of the table will be maintained in true horizontal position irrespective of the rocking movements of the ship.

To this end the invention essentially consists of a weighted conical shaped member upon which the table top is mounted, the member being suitably supported for oscillatory movement in any direction whereby uniform equilibrium of the top will be maintained regardless of the tilting movements of the ship.

Other objects will appear as the nature of the invention is better understood, the same residing in the specific construction, combination and arrangement of parts herein-after more fully described.

In the drawing forming a part of this application like numerals of reference indicate similar parts in the several views and in which:

Figure 1 is a perspective view. Fig. 2 is a vertical sectional view.

Referring more particularly to the drawing 5 designates the floor of the ship, or other suitable support, upon which is fastened the base plate 6. Rising from the base plate 6 is a rod 7 terminating to provide a pointed end portion 8 that swingingly supports the conical shaped member 9, the latter having fixed thereto the table top 10.

The conical shaped member 9 is closed at its small end by means of a plug 11 of any suitable material, into which the pointed end of the rod 7 partially projects, when the parts are operatively associated as clearly shown in Fig. 2, whereby the member 9 is supported at its apex for lateral swinging movement. The member 9 may be of any

desired length, but spaced from the floor to 50 permit of this movement, and may also be constructed from any suitable material, preferably some light metal, having a ring 12 of some weighted material secured to the inner periphery thereof adjacent its lower 55 end, whereby said member under the influence of the weight will always assume and maintain a true perpendicular position with respect to the floor of the ship regardless of what the rocking and tilting movements of 60 the ship might be.

Secured to the exterior of the member 9 at a suitable point below the apex thereof is a circumferential series of L-shaped bracket arms 13, the horizontally disposed 65 flanges 14 of which support the table top 10 to which they are secured in any suitable manner. Fixed to the plug 11 at the top of the conical shaped member 9, is the body portion of a bracket 15, having radially projecting arms 16 upon which is supported a relatively small table top 17 to which they are secured in any suitable manner. In addition to possessing an oscillatory movement, the conical shaped member 9 is free 75 to revolve, whereby the table may be used in the capacity of a self-serving table if so desired.

It is believed that from the foregoing description the nature and advantages of the 80 invention will be readily apparent without requiring a more extended explanation and therefore the same has been omitted. However I desire to have it understood that I do not limit myself to the precise construction herein disclosed, the same being merely 85 illustrative of one embodiment of the invention, and that various changes in the construction, arrangement and proportions may be resorted to when desired as fall within 90 the scope of the appended claim.

What I claim is:

A self leveling table for ships, comprising a base, a rod rising centrally therefrom and terminating in a point, a conical shaped hollow member surrounding said rod, a plug 95 closing the small end of said member and having a notch for the reception of the

pointed end of said rod, a table top fixed to said plug and disposed exteriorly of said member, and a weighted element of uniform dimensions secured to the inner periphery 5 at the lower end of said member for maintaining the member and table in a true perpendicular relation to the deck of the ship.

In testimony whereof I affix my signature in presence of two witnesses.

JOHN P. MURCZKO.

Witnesses:

Jos. L. KOCHESS,
JOHN POHORERIES.
